UNITED STATES PATENT OFFICE.

HENRY KIELBERG, OF MARTINS FERRY, OHIO, ASSIGNOR TO WHEELING STEEL CORPORATION, OF WHEELING, WEST VIRGINIA, A CORPORATION OF DELAWARE.

BARREL CLEAT.

Application filed June 16, 1924. Serial No. 720,249.

To all whom it may concern:

Be it known that I, HENRY KIELBERG, a citizen of the United States of America, and resident of Martins Ferry, county of Belmont, and State of Ohio, have invented certain new and useful Improvements in Barrel Cleats, of which the following is a specification.

This invention relates broadly to securing means for the heads of barrels and kegs, and more specifically to a barrel cleat.

The primary object of the invention is to provide a simple and inexpensive cleat for barrel heads which is so formed that, following application, it effectually resists all tendency to become loosened or detached in service.

In describing the invention in detail, reference is herein had to the accompanying drawings, in which—

Figure 1 is a section of an end portion of a barrel, showing the application thereto of my invention;

Figure 2 is an end elevation of a barrel, showing the invention applied thereto;

Figure 3 is a detail sectional view showing the manner of attachment of an end portion of the invention;

Figure 4 is an enlarged side elevation of the cleat;

Figure 5 is a similar view of a modified form of the cleat; and—

Figure 6 is a section on line 6—6, Fig. 5.

Referring to said drawings, 1 indicates the body, 2 the head, and 3 the chime of a barrel or keg of the general type to which my invention is applied for supporting or reinforcing the barrel head against strains.

The cleat is designed to be mounted diametrically of the barrel head, and it comprises a single sheet metal member which is shaped intermediate its ends to form a body 4 of substantially angle-iron form. The opposite side portions of said body are adapted to have their edges seat upon and to form opposite acute angles with the barrel head 2, as shown in Fig. 1. The opposite end portions of the cleat are flat and are bent to form downturned hooks 5 adapted to fit upon or over the chime 3 of the barrel and to be rigidly attached to the barrel body 1, as by nails or brads 8.

Provided in each of the oppositely inclined side portions of the cleat body 4 is

a plurality of holes 7 designed to receive 55 nails 6 by which said body is rigidly attached to the barrel head, said holes being of a size so nearly approximating the diameters of the nails employed that the latter must be directed substantially at right angles to said side portions and, therefore, must enter the barrel head at an angle to the plane of the latter. Thus, the said nails 6 directed through one side portion of said cleat body cross the plane of the nails in the other side 65 portion, as shown in Fig. 1, in effect keying the body of the cleat to the barrel head in such manner that tendency of said cleat to become loosened is effectually resisted.

In the modified form of cleat shown in 70 Figs 5 and 6 a central longitudinal bead-like reinforcing rib 4^a is pressed in the body 1, whence the side portions of said body incline divergently, as is best shown in Fig. 6.

What is claimed is—

1. In a sheet metal barrel cleat, a body of approximately angle-iron form designed for mounting with the edges of its relatively inclined side portions seated upon a barrel head, said body being adapted to have attaching nails directed substantially at right angles through said side portions whereby said body is keyed to the barrel head.

2. In a sheet metal barrel cleat, a body of approximately angle-iron form designed for 85 mounting with the edges of its side portions resting upon a barrel head, said side portions being oppositely inclined with respect to the barrel head and provided with nail holes adapted for the guidance of attaching 90 nails into the barrel head in crossing relation.

3. In a sheet metal barrel cleat, a body having hook-like terminals for embracing the chime of a barrel, said body being of substantially angle-iron shape and being adapted to seat with its free edges in engagement with the barrel head, each of the relatively inclined side portions of said body having therein holes for the reception and 95 guidance of attaching nails at substantial right angles thereto, whereby such nails directed into the barrel head are made to occupy intersecting planes for keying said body to the barrel head.

In testimony whereof, I affix my signature.

HENRY KIELBERG.
